UNITED STATES PATENT OFFICE

JOHN J. McCARTHY, OF MALDEN, MASSACHUSETTS

DESIGN FOR A COMBINED DOME LIGHT AND SPEECH TRANSMISSION DEVICE

Application filed May 2, 1930. Serial No. 35,476. Term of patent 14 years.

To all whom it may concern:

Be it known that I, JOHN J. McCARTHY, a citizen of the United States, and residing at Malden, in the county of Middlesex and State of Massachusetts, have invented a new, original, and ornamental Design for a Combined Dome Light and Speech Transmission Device, of which the following is a specification, reference being had to the accompanying drawings, forming part thereof.

Referring to the drawings;
Fig. 1 is a side view, and
Fig. 2 is a plan view.

What I claim is

The ornamental design for a combined dome light and speech transmission device, as shown.

In witness whereof I hereunto subscribe my name this 23d day of April, 1930.

JOHN J. McCARTHY.
